(57) CLAIM

The ornamental design for a utility loader as shown and described.

DESCRIPTION

FIG. 1 is a rear, right side, top, perspective view of a utility loader showing the claimed design;

FIG. 2 is a right side view thereof; and,

FIG. 3 is an enlarged rear, right side, top, perspective detail view of the portion 3 identified in FIG. 1, a rear, left side, top perspective view of this portion being a mirror image thereof.

The broken lines in the drawings illustrate portions of the utility loader that form no part of the claimed design. The dot-dash broken lines depict the boundaries of the detail enlargement and form no part of the claimed design.
